Patented Aug. 1, 1922.

FIG. 1.

FIG. 2.

FIG. 3.

FIG. 4.

Inventor,
Nicholas Nesser,
By Llynnforth, for Clinton Miller,
Attest.

UNITED STATES PATENT OFFICE.

NICHOLAS NESSER, OF CHICAGO, ILLINOIS, ASSIGNOR TO NESSER & COMPANY, OF CHICAGO, ILLINOIS, A CORPORATION OF ILLINOIS.

GOLF BAG.

1,424,317.

Specification of Letters Patent. Patented Aug. 1, 1922.

Application filed October 24, 1921. Serial No. 510,066.

To all whom it may concern:

Be it known that I, NICHOLAS NESSER, a citizen of the United States, residing at 207 South Green Street, Chicago, in the county 5 of Cook and State of Illinois, have invented a new and useful Improvement in Golf Bags, of which the following is a specification.

This invention relates to improvements in 10 golf-bags and more especially to a golf-bag having a bottom that can be easily and cheaply made, is neat in appearance and strong and durable.

A device embodying the features of my 15 invention is shown in the accompanying drawings, in which:

Fig. 1 is a view of a golf-bag in side elevation, Fig. 2 is a view in side elevation of the bottom of the bag showing the metal reinforcing plate, Fig. 3 is a bottom plan view of the bag, and Fig. 4 is a view taken as indicated by the line 4 of Fig. 3.

Since the features of my invention relate primarily to the bottom of the bag, the upper part thereof may be of any desired construction; and accordingly I have shown in Fig. 1 a bag of the ordinary cylindrical form, the body of which is made of canvas 20 or other suitable material which may be 25 stiffened in any well known manner, if desired. At the top of the bag there is a reinforcing strip of leather 21 and the bag is provided with the usual strap 22 for carrying. If the body 20 is made of canvas, I 30 preferably sew to the outer face thereof at the lower end a strip of leather 25 of sufficient thickness to stiffen the canvas and furnish protection and reinforcement thereto. This strip of leather 25 is preferably supplemented by a second reinforcing strip 26 35 of cardboard or other suitable material interposed between the canvas and the leather, as clearly shown in Fig. 4, the bottom edges of the leather strip 25 and cardboard strip 40 45 26 extending to the bottom edge of the canvas body part 20. The bottom of the bag comprises primarily a cap 35 made of rawhide. This cap 35 comprises a central disk-like portion 36. Extending downwardly 50 55 from this central disk-like or body portion is an annular flange 37, and at the bottom is a short outwardly projecting flange or portion 38 connecting the flange 37 with an outer upwardly projecting flange 39 which, as shown, is preferably slightly wider than

the flange 37. When the parts are assembled the material constituting the body of the bag such as the canvas 20 and any reinforcing strips that may be employed, such as the leather 25 and cardboard 26, are all extended 60 down into the annular channel formed between the flanges 37 and 39. A row of stitching 42 is then sewed around the bottom, the stitches passing through the two flanges 37 and 39, and through the body portion 20 and any reinforcing strips that may be employed. Such stitching holds the body portion 20, and any such reinforcing strips, in the annular channel formed between the flanges 37 and 39. The upper edge of the 70 reinforcing strip 25 may be sewed to the body portion 20 by stitching, as indicated by 45, if desired. A metal reinforcing piece 50 made in any well known manner may be provided at one side where the ends of the 75 reinforcing strip 25 join. This reinforcing strip has its lower end folded up against the bottom and riveted as by the rivets 52.

The stitching 42 is preferably applied, as shown, in an upwardly and outwardly 80 sloping position. When thus applied the complete ring of stitches comprise a frusto conical suspension for the bottom whereby the stiffness of the outer portion 39 of the channel is utilized to aid the stiffness of the 85 inner portion 37 in supporting the load within the bag resting on the bottom disk 36.

The bottom cap 35, as has been stated, is made of rawhide. It is best formed in the shape shown by first wetting the hide to 90 soften it, and then pressing it into the shape shown with any suitable die or press. The stitching 42 is preferably put in when the hide is still wet; or if it has been formed into the shape shown and then allowed to 95 dry, it may be again moistened and then stitched. After the stitching has been put in, the cap 35, after it is dry, may be varnished or otherwise protected against moisture. After the cap 35 has become dry, and 100 after it is varnished, it will become very stiff and hard resembling metal in some respects.

While I have shown and described certain embodiments of my invention, it is to be 105 understood that it is capable of many modifications. Changes, therefore, in the construction and arrangement may be made without departing from the spirit and scope of the invention as disclosed in the appended 110

claims, in which it is my intention to claim all novelty inherent in my invention as broadly as possible in view of the prior art.

What I claim as new, and desire to secure 5 by Letters Patent, is:

1. A golf bag comprising an integral raw hide bottom formed of a disk of said material having downwardly turned edges, the material of said edges being upwardly turned parallel with said downwardly turned portions to provide an annular channel, said upwardly turned portions rising above the plane of said disc, material forming the body of the bag extending into said 10 channel and stitching passing through both walls of said channel and said body material closely adjacent the plane of said disc.
2. A golf bag comprising an integral raw hide bottom formed of a disc of said material having downwardly turned edges, the material of said edges being upwardly turned and extending to a plane above the plane of the disc, material forming the body of the bag extending into said channel, a 15

reinforcing band extending into said channel about said body material and stitching passing through both walls of said channel, said body material and said reinforcing band closely adjacent the plane of said disc. 25

3. A golf bag comprising an integral raw hide bottom formed of a disc of said material having downwardly turned edges, the material of said edges being upwardly turned and extending to a plane above the plane of the disc, material forming the body 30 of the bag extending into said channel, a reinforcing band extending into said channel about said body material and stitching passing through the inner wall of said channel closely adjacent said disc and sloping 35 outwardly and upwardly through the body material and the reinforcing band and passing through the outer wall of said channel above the plane of the disc. 40

In testimony whereof I have hereunto set 45 my hand and seal this 2nd day of September, 1921.

NICHOLAS NESSER.
